SHOE CONSTRUCTION

Luigi Pignanelli, Portland, Oreg., now by judicial
change of name Louis Pinell

Application September 23, 1931, Serial No. 564,512

4 Claims. (Cl. 36—43)

This invention relates to shoe construction, and more particularly is an improvement in the manner of producing the counter portion of a shoe.

A primary object of the invention is the provision of a shoe wherein that part of the rear or heel portion constituting the supporting counter is constructed to eliminate any possibility of cracking as is not infrequently the case in shoes as heretofore built where the counter is produced from a strip of approximate rectangularly-shaped leather. Such cracking in the conventional counters as heretofore built, which cracking occurs along the line of bending, is a result of the fact that in order to afford a horizontal inwardly-directed flange the lower edges are feathered and subsequently rived to take care of the excess material, the feathering materially weakening the leather.

A further object of the invention is the provision of a shoe counter formation wherein permanency of shape is given to the same in that the wing portions of the counter are inter-connected along lower edges of each.

A still further object is the provision of a shoe counter wherein greater structural strength is obtained by a continuation of the same as the insole portion of the shoe.

A still further object is the provision of a structural arrangement affording a most comfortable, flexible, and durable women's shoe of the sandal character and which may be produced in a more simplified and inexpensive manner.

The foregoing, together with further and more particular objects and advantages, should become apparent throughout the course of the following detailed description and claims, the invention consisting in the novel construction, adaptation and combination of parts hereinafter described and claimed.

40 In the drawing:

Figure 1 is an underenath plan development representing the configuration of a blank from which the present invention is produced.

Fig. 2 is a perspective view of the same in the formation assumed as a shoe counter and insole.

Fig. 3 is a fragmentary side elevational view of a shoe embodying the present conception, parts being broken away and shown in longitudinal vertical section.

50 Fig. 4 is a transverse vertical section taken through the vamp portion of a shoe as represented in Fig. 3.

Fig. 5 is a side elevation of a sandal-type women's shoe produced by the present invention; and

Fig. 6 is a transverse vertical section taken through the vamp portion of a shoe such as represented in Fig. 5.

Reference being had to Fig. 1 of the drawing, the numeral 5 generally represents a blank from which the preferred inventive embodiment is formed, said blank stamped from leather or other suitable material into an elongated strip, the fore part 6 of which is configured to the approximate shape of the toe portion of a shoe insole and the rear part 7 having lateral wings 8, 9 projecting from opposite sides of the same, side edges of said wings being suitably tapered to feathered edges 10, 11, and companion ends oppositely dressed to provide meeting feathered edges 12, 13. The rear portion of said part 7, moreover, provides a re-entrant notched opening 14 serving to receive, in the assembling of said rear part 7 into a shoe counter, a projecting tongue element 15, said assembling accommodated by a bending 20 of the lateral wings on lines indicated by X, the feathered edges 12, 13 being aligned over one another and cemented together.

In the lasting operation of the shoe illustrated, the assembled counter with the integral insole 25 portion 6 projecting therefrom is applied over the last. The shoe upper 20 is drawn over the counter and the vamp portion of the last, the edges of the upper being turned in over the sole portion, a strip of leather 21 applied along the 30 ball portion of the inturned edges, and the layers stitched. The outsole 22 is subsequently secured along the protruding welt portion of such strip 21 and the heel 23 applied. A fabric or thin leather sock lining 25 is preferably introduced 35 within the heel portion and sewed along the edge to the shoe upper. 24 represents a heel pad.

More particularly to Fig. 5, indicating a modified use of the counter formation described, I represent a shoe design of a character somewhat 40 similar to the Deauville sandal, providing, however, the one-piece upper 30 for the heel portion to afford sufficient rigidity in maintaining the shape, and with a portion 31, serving as a vamp, being brought down and turned in over the forwardly projecting sole portion 32. An insole 33 may be inserted within the shoe and stitched with the vamp edges and the sole 31.

While I have herein illustrated and described the preferred structural formation and use of the 50 invention, it is not my intention to in any way confine the same except as may be limited by the scope of the hereto annexed claims.

What I claim, is,—

1. A blank for a shoe counter member pre- 55

senting a toe portion, a heel portion, and wings projecting laterally of said heel portion, the rear edge of said heel portion presenting a transverse tongue and a longitudinal slot of the approximate plane dimensional shape of said tongue, said wings being adapted to be bent upwardly at approximate right angles to the plane of the heel and the rear edges thereof being adapted to be united in the approximate median line of the blank, said tongue being adapted to align itself into the slot of the heel to provide a substantially continuous surface to the same.

2. A counter member for a shoe presenting a toe portion, a heel portion, and upstanding wing elements at the opposite sides of the heel portion, said wing elements having interconnected terminal ends extending about the rear of the heel portion, said heel portion having a slot in the same and one of said interconnected ends of the wing elements providing a tongue interfitting in said slot, said tongue and the heel portion collectively providing a substantially continuous seating surface in the heel of the counter member.

25 3. The method of forming a counter member for a shoe consisting in stamping a material

blank to provide a toe portion, a heel portion, and wings extending laterally from both sides of the heel portion with one of the wings presenting a tongue element and the heel portion presenting a rearwardly directed slot of the approximate plane dimensional shape of the tongue element, bending said wings upwardly at right angle to the plane of the heel portion, drawing the rear edges of the wing elements together at the rear of the heel portion to locate the tongue in the slot, and uniting the meeting edges of the wing elements.

4. The method of producing a counter member for a shoe consisting in forming a material blank to provide a heel portion having a wing element of a length in excess of that of the heel portion and extending laterally of the heel portion with said extended portion of the wing element presenting a tongue and the heel portion presenting a slot of the approximate plane dimensional shape of the tongue, and inserting said tongue in the slot co-incident with a bending of the wing element upwardly at right angles to the plane of the heel portion.
